UNITED STATES PATENT OFFICE.

WILLIAM MASON, OF HARTFORD, CONNECTICUT, ASSIGNOR TO THE COLTS
PATENT FIRE-ARMS MANUFACTURING COMPANY, OF SAME PLACE.

BREECH-LOADING FIRE-ARM.

SPECIFICATION forming part of Letters Patent No. 247,378, dated September 20, 1881.

Application filed July 14, 1881. (No model.)

To all whom it may concern:

Be it known that I, WM. MASON, of Hartford, in the county of Hartford and State of Connecticut, have invented a new Improvement 5 in Breech-Loading Fire-Arms; and I do hereby declare the following, when taken in connection with the accompanying drawings and the letters of reference marked thereon, to be a full, clear, and exact description of the same, 10 and which said drawings constitute part of this specification, and represent, in—

Figure 1, a longitudinal sectional view, the parts in their place of rest; Fig. 2, the same view with the barrels tilted; Fig. 3, the same 15 view as in Fig. 1 with the arm as in the cocked position; Fig. 4, a transverse section of the lever.

This invention relates to an improvement in that class of breech-loading fire-arms in which 20 the barrel or barrels are arranged to tilt up at the breech for the insertion of the cartridge, and particularly to that class of such arms in which the hammer is arranged within the receiver, and commonly called "concealed hammers," the object of the invention being to cock 25 the hammer as the barrels are tilted, also to partially apply the pressure of the mainspring, and then, in the return of the barrels, complete that pressure; and it consists in combining 30 with the tilting barrels and concealed hammer a lever hung upon a pivot between the hammer and the pivot on which the barrels turn, one arm extending to the hammer to engage it forward of its pivot, the other arm extending for- 35 ward and engaging the barrels forward of their pivot, so that the tilting barrel will depress the forward end of the lever and correspondingly raise the rear end and throw the hammer back to full-cock; also, in the arrangement of the 40 mainspring, one end of which is seated on the said lever, the other end bearing upon the hammer forward of its pivot, whereby the spring is partially applied in tilting the barrels and completed in their return, as more fully herein- 45 after described.

A represents the receiver, from which an arm, B, extends forward to form a bearing for the pivot on which the barrels C turn, in the usual manner for this class of fire-arms.

D is the hammer, hung upon a pivot, a, within 50 the receiver, and so as to strike through the recoil-plate or upon the firing-pin therein, and provided with a sear, E, all in the usual and well-known manner. The usual pivot on which the barrels turn is indicated in broken lines in 55 the drawings.

The receiver is constructed with a recess, F, forward of the hammer and through to the end of the arm B'. In this recess the cocking-lever is hung upon a pivot, d, one arm, H, extending 60 toward the hammer and so as to engage beneath the shoulder e on the hammer forward of its pivot, as seen in Fig. 1. The other arm, L, extends forward and engages in a recess, f, in a projection, I, extending down from the 65 barrels and forward of the pivot on which the barrels turn, so that as the barrels are tilted from the position seen in Fig. 1 to that in Fig. 2 the forward end of the lever, being forward of the pivot of the barrels, is depressed, which 70 causes the rear end to rise, and that end, being in engagement with the hammer, turns the hammer to full-cock, as seen in Fig. 2. The lever L is recessed upon its under side, as seen in Fig. 4. The mainspring is arranged in this 75 recess. This mainspring is of the usual V shape. One end, h, takes its seat directly on the lever, the other, i, on a seat, n, formed on a projection of the hammer which extends forward for that purpose, as seen in Fig. 1, and 80 should be forward of the point where the lever engages the hammer.

As the barrels are tilted the end H of the lever rises, carrying with it the hammer, as before described. The movement of the hammer 85 carries up the end i of the mainspring, and, being forward of the point where the lever engages the hammer, that end of the mainspring moves proportionately faster than the lever, and to the extent that it thus moves faster the 90 spring is compressed, as seen in Fig. 2. Then, when the barrel is returned, the other end of the spring is pressed down, as seen in Fig. 3, completing the application of the spring and taking the lever out of the way of the hammer, 95 so as to leave it free for discharge.

In order to cover the forward end of the recess F, within which the lever is placed, the

lever is constructed with a projection, *m*, on its upper side, forming a shoulder corresponding to the end of the receiver, as at *r*, and on the under side is a similar projection, *s*, forming a shoulder extending over the forward end, *t*, the extent of these projections being such, as shown, so that when the lever is up, as seen in Fig. 1, the lower part of the opening is closed by the projection *s*, and when down the upper part of the recess is closed by the projection *m*, as seen in Fig. 2, and so that it is impossible for any foreign or disturbing substance to enter at that end of the recess *F*.

While I prefer the arrangement of mainspring as shown and described, it will be evident that the mainspring may be otherwise applied, the operation of the lever to cock the hammer remaining the same.

I do not broadly claim the arrangement of a lever in the receiver of a tilting-barrel fire-arm, so that the tilting of the barrel will, through the action of the lever, cock the hammer; nor do I broadly claim such an arrangement when the mainspring is arranged so that its force is partially applied in tilting the barrel, the application completed by the return of the barrels, as such is shown in my applications for Letters Patent filed May 12, 1881; but

What I do claim is—

1. In a tilting-barrel fire-arm, the combination therewith of a hammer, a lever hung upon a pivot between the pivot of the hammer and

the pivot on which the barrels turn, one arm extending rearward into engagement with the hammer forward of its pivot, the other extending forward into engagement with the barrel or barrels forward of their pivot, substantially as and for the purpose described. 35

2. In a tilting-barrel fire-arm, the combination therewith of a hammer, a lever hung upon a pivot between the pivot of the hammer and the pivot on which the barrels turn, one arm extending rearward into engagement with the hammer forward of its pivot, the other extending forward into engagement with the barrel 45 or barrels forward of their pivot, and a V-shaped mainspring one end of which is seated on the said lever, the other on the hammer forward of its pivot, substantially as described.

3. In a tilting-barrel fire-arm, the combination therewith of a hammer, a lever hung upon a pivot between the pivot of the hammer and the pivot on which the barrels turn, one arm extending rearward into engagement with the hammer forward of its pivot, the other extending forward into engagement with the barrel or barrels forward of their pivot, the lever constructed with projections at its forward end to close the end of the recess in which the lever is arranged, substantially as described. 50

WM. MASON.
